[57] CLAIM

The ornamental design for a combination pool and sandbox, as shown.

DESCRIPTION

FIG. 1 is a perspective view showing the design of the combination pool and sandbox of the present invention in the open position thereof;

FIG. 2 is a top plan view of the combination pool and sandbox illustrated in FIG. 1;

FIG. 3 is a side elevational view of the combination pool and sandbox illustrated in FIG. 2;

FIG. 4 is a bottom elevational view of the combination pool and sandbox of FIG. 2;

FIG. 5 is a perspective view of the combination pool and sandbox illustrated in FIG. 1 in the closed position thereof;

FIG. 6 is a front elevational view of the combination pool and sandbox illustrated in FIG. 5; and

FIG. 7 is a rear elevational view of the combination pool and sandbox illustrated in FIG. 5.
